UNITED STATES PATENT OFFICE.

CHARLES B. ELLIOTT, OF RIVERSIDE, CONNECTICUT.

PLAYING-BALL.

SPECIFICATION forming part of Letters Patent No. 731,026, dated June 16, 1903.

Application filed December 3, 1902. Serial No. 133,668. (No model.)

To all whom it may concern:

Be it known that I, CHARLES B. ELLIOTT, a citizen of the United States, and a resident of Riverside, in the county of Fairfield and State 5 of Connecticut, have invented certain new and useful Improvements in Playing-Balls, of which the following is a specification.

My invention relates to improvements in playing-balls, applicable more particularly to golf-balls.

The object of my invention, among other things, is to provide golf and other playing balls of good quality at a comparatively small cost; and to this end my invention consists 15 in winding the interior or body of the ball of fibrous material—such as yarn, strips of textile or woven fabric, or the like—the same being impregnated with rubber material which in winding the ball is stretched with and by 20 stretching the fibrous material. The body of the ball may be formed by winding the said material upon itself or it may be wound upon a wooden or other core. The filaceous or filamentous material selected should possess 25 elastic properties, and by preference this material is first saturated with a solution of india-rubber, so as to become more or less homogeneous with the fibrous base, and in winding the ball the fibrous material and rubber are 30 stretched to the limit—that is, the same is stretched to the extent allowed by the fibrous material or to any degree short of the breaking-point. In this way the ball can be wound 35 with great facility and at the same time with practical uniformity throughout and without overstretching the material composing the body of the ball.

In the accompanying drawings, to which reference is made and which form a part of 40 this specification, Figure 1 is a sectional view of a golf-ball made in accordance with my invention. Fig. 2 shows a portion of tape or strip of which the body of the ball is wound, and Fig. 3 shows a portion of a fibrous yarn 45 of which the body of the ball may be wound.

In the drawings, 2 designates the interior body of the ball; 3, the core, which may be used or not, as desired; 4, an outer shell or cover, preferably of hard india-rubber or 50 gutta-percha.

5 designates a strip or tape of textile or

woven fabric, and 6 the yarn or string which may be used in place of the strip or tape.

In preparing the strip or tape 5 or yarn 6 I impregnate the same with soft india-rubber 55 or similar elastic material, and for this purpose I prefer a pure india-rubber solution dissolved by naphtha, benzene, or other solvent. Into this solution I immerse this textile material (the strip or yarn) and after removal 60 allow the same to dry. The textile material may be immersed any suitable number of times according to the thickness of coating desired. In winding the ball the material is stretched to practically the limit of the textile or twisted fabric, and the winding is continued in this way until the proper size is reached. Then the outside cover is applied in the usual way.

In selecting the textile fabric I prefer a 70 strip of stockinet or other very elastic fabric, and when yarn is used I prefer loosely-twisted woolen yarn; but I do not limit myself to these materials.

By my invention the woven or twisted material is elastic, but less elastic than the rubber incorporated with it, and is of sufficient strength so that when stretched to the limit it will not break in winding, but the winding will be uniform and the india-rubber will be 80 uniformly distributed throughout the whole body of the ball. In other words, when stretching of the strand occurs the bulk of the strand (the width or diameter) lessens, and if the stretching is not uniform the building up by 85 the winding will be irregular and the density of the ball will not be uniform. By my invention the stretching is regulated to a nicety throughout and the winding is uniform, and the density of the ball is uniform and the india-rubber is uniformly distributed throughout 90 the body of the ball.

Having thus described my invention, what I claim as new, and desire to secure by Letters Patent, is—

1. A playing-ball comprising a main body composed of elastic fabric impregnated with soft india-rubber or similar material stretched and wound to proper size, substantially as described.

2. A playing-ball comprising a main body composed of woven elastic fabric impregnated

with soft india-rubber and stretched and wound to proper size, substantially as described.

3. A playing-ball comprising a main body composed of stockinet impregnated with soft india-rubber and stretched and wound to proper size, substantially as described.

4. A playing-ball consisting of a main body

composed of elastic fabric impregnated with soft india-rubber stretched and wound to proper size and a cover, substantially as described.

CHARLES B. ELLIOTT.
